FILING DRUM

Richard P. Scholfield, New York, N. Y.

Application July 3, 1945, Serial No. 603,025

4 Claims. (Cl. 129—16)

1

The present invention relates to rotary files of the type comprising a rotatably mounted drum adapted to have a plurality of filing cards removably secured upon its periphery, for ready access to the cards by an operator, for inspection or for the posting of entries thereon.

An object is to provide on the filing drum improved card retaining means.

A further object is to provide improved card separators or card guides, to divide the cards into groups and sub-groups and to maintain the cards aligned on the drum and to prevent angular displacement thereof, that is, to maintain the inner and outer edges of the cards on line parallel to the axis of the drum.

Another object of the invention is to provide a novel type of filing card and a novel type card retaining means, adapted to increase the area of the surface of the cards available for the reception of printed, typed or written matter. To this end, instead of having portions of the cards removed and eliminated by keyhole shaped slots, or the like, punched therein, to embrace card retaining rails, the cards may be provided along their inner edges, with dove-tail shaped tabs, adapted to be received in an under-cut groove or channel of corresponding cross sectional shape, formed in the periphery of the rim of the drum, to secure the cards in place. Another advantage resulting from this construction is that a plurality of cards may be removed en bloc, by simply twisting them laterally so that the inclined side edges of their tabs are removed from the under-cut portion of the groove.

A further object of the invention is to provide special means for removing cards of the last mentioned type from the rim of the drum en bloc, in large groups, without twisting. To accomplish this aim, certain sections of one side wall of the undercut groove are made laterally movable to widen the groove and thereby permit direct translational removal of the dove-tail tabs therefrom. Of course, the invention is not limited to the use of the specific dove-tail shape shown in the accompanying drawings and described below, as any headed tap shape, having a laterally enlarged portion and a restricted neck may be employed, in combination with a laterally enlarged groove having a mouth of restricted width.

Other and further objects and advantages of the invention will be apparent to those skilled in the art from a consideration of the specific embodiments shown for purposes of illustration in the accompanying drawings and described below.

2

Figure 1 is a side elevation of a preferred form of drum.

Figure 2 is a half section and partial front elevation of the drum of Figure 1.

Figure 3 is a fragmentary section, showing a filing card, guide card or separator and the supporting means therefor in elevation.

Figure 4 is a central, vertical section, on an enlarged scale, on the card of Figure 3.

Figure 5 is a sectional elevation of a modified form of separator or card guide.

Figure 6 is a side elevation of the device of Figure 5.

Figure 7 is a sectional view of the drum rim and an elevation of card and

Figure 8 is a section on an enlarged scale, showing the laterally movable portion of the side wall of the undercut groove.

Referring to Figures 1 and 2, the rotatable filing drum proper is mounted for rotation upon a fixed, horizontal shaft 10 carried by any suitable supporting structure, such as the socket members 11, 12, provided with laterally and downwardly projecting legs 13. Since the shaft 10 and the supporting structure form no part of the invention of the present application, they are shown merely diagrammatically in the accompanying drawings and need not be further described. Of course, any of the supporting structures, brakes, clutches and operating mechanisms shown in prior Patents Nos. 2,046,655 and 2,205,932 and in the patent to Scholfield and Kelly No. 2,536,574, may be employed with the filing drum of the present application.

The drum includes a pair of spaced heads 14, 14', each comprising a web 15, having a central tubular boss 16, journaled on the shaft 10, and radially extending reinforcing ribs 17, extending outwardly from the boss to a plurality of dished or inwardly recessed portions 18, 19, 20, each terminating at its outer end in a section 21 of substantial length, axially of the drum, and curved to lie on a surface concentric with the axis of the drum. Each section 21 is provided with a plurality of apertures 22, 23, 24, for the reception of screws, or the like, 25, to connect the drum heads to the rim in any one of a plurality of different positions, as hereinafter explained.

The drum heads are further provided with circumferentially continuous radial flanges 26, disposed adjacent to the side edges of the cards mounted on the rim.

The drum heads 14, 14' may be of any suitable material, but, preferably, are cast aluminum, or

the like. If desired, drawn or stamped sheet metal or molded plastic material may be used.

The rim 27, preferably is made from cast metal, such as aluminum, and accurately machined.

The rim of the drum is shaped to provide a circumferentially extending undercut groove or channel 32, defined by a cylindrical bottom 33 and inclined side walls 34, 35. The channel is adapted to serve as means for securing to the rim, a plurality of different types of devices, as 10 hereinafter explained.

As indicated in Figure 8, spaced arcuate sections of suitable length, along one side wall of the undercut groove, are mounted for lateral movement relative to the opposite side wall, so 15 as to widen the groove, when they are shifted, to permit translational insertion or withdrawal of devices shaped to conform to the cross sectional shape of the groove. These devices are adapted to be retained in the groove, by a dovetail joint connection when the movable sections are in their normal or "closed" position. To this end, arcuate strips 37 of suitable length, disposed in laterally enlarged portions 38 of the groove, carry pins or lugs 39; projecting downwardly through guide slots 40 in the rim, to positions inwardly thereof, where they are connected to coil compression springs 41, by means of lateral projections 42, the springs being held at their other ends by similar lugs 43, depending from the rim and having lateral projections 44 thereon. The laterally movable wall section of the undercut groove makes it possible to insert in the groove, a member shaped to conform thereto, to be retained therein.

As indicated in Figures 3 and 4, guide cards or separators 45, provided with inwardly projecting tabs 46 adjacent their inner edge 47 may be retained on the rim by an interfitting relation between the tab and the undercut groove. 40 The tab may be covered by a metal sheath 48, to withstand wear, and to make the guide cards extremely long-lived. The tabs may be inserted in the dovetail groove by aligning the tabs longitudinally with the groove and by then turning the cards transversely, so that they assume the position shown in Figures 3 and 7.

As indicated in Figures 5 and 6, short rod sections 55, having a cross section conforming to the cross section of the groove 32 may be employed as a supporting means for guide cards 50 or separator wires 56, projecting through apertures 57 in the sections and extending upwardly therefrom, for pivoting movement with respect thereto. These rod sections may be inserted in the groove by shifting the laterally movable side wall section 37, as explained above. The rod sections 55 are preferably mounted for free sliding movement in the groove, and need only be of sufficient length to prevent lateral turning of the guide elements 50 or 56 carried thereby. The guides or separators serve to prevent lateral tipping of the cards and to divide the circumference of the drum into a plurality of different sections, which are adjustable in size and capacity relative to each other, for the reception of different groups of cards.

As shown in Figure 7, filing cards 60 may be provided with integral dove-tail tabs 61 on their lower margins, adapted to be received in the undercut groove 32, formed in the surface of a cylindrical rim 27. The cards may be inserted by the use of a movable side wall section, as indicated in Figure 8, or simply by slightly distorting or bending the tabs 61, or the corners 75

thereof, or by swinging the cards about a central vertical axis, to permit the tab to be inserted or removed from the channel.

It will be understood that such cards may be removed en bloc from a drum of the type shown in Figures 7 and 8 by shifting the movable side wall section 37 to "open" the groove and permit translational withdrawal of the dove-tail tabs from the groove.

It is thought that the structure and mode of operation of the apparatus of the present invention will be entirely clear to those skilled in the art from the foregoing description and the accompanying drawings. However, it should be understood that the invention is not limited to the details shown and described, but covers all modifications coming within the scope of the appended claims and their equivalents.

I claim:

1. A rotatable filing drum comprising a rim having means associated therewith defining a circumferentially extending, undercut groove having diverging, fixed and rigid side walls, with the exception of certain sections of at least one of said side walls, which sections are translationally laterally movable, to increase the width of said groove adjacent said sections, for the insertion into said groove of means having inclined sides, complementary in shape to the undercut groove, and means for holding the movable sections in alignment with the fixed sections to maintain the groove in the narrow condition.

2. A rotatable filing drum comprising a rim having its surface shaped to provide a circumferential channel having a mouth of fixed and restricted width except at spaced sections and being laterally enlarged therebelow, said spaced sections of the mouth of the channel being defined by strips mounted for lateral translation movement relative to the other side of the channel, to increase the effective width of said mouth, said channel, when the width of the mouth is so increased, being adapted to receive securing means for card separators, complementary in shape, with the cross-sectional shape of the channel, and means for holding the movable strips in alignment with the fixed sections of the mouth to maintain the width of the mouth in the narrow condition.

3. A filing drum comprising a rim, means associated therewith defining a circumferentially extending undercut groove, said means being in part fixed and relatively immovable and in part translationally movable to widen the groove for the introduction or removal of an element adapted to be retained in the groove when narrowed, and means for holding said movable means in alignment with said fixed means to maintain the groove in the narrow condition.

4. A filing drum comprising a rim having means associated therewith defining a circumferential undercut groove having fixed side walls, except at spaced sections, said sections of one side wall of the groove being translationally laterally movable to widen the groove for the introduction or removal of an element adapted to be retained in the groove when narrowed, and resilient means urging said spaced sections toward the opposite side wall to maintain the groove normally in the narrowed condition.

R. P. SCHOLFIELD.
